UNITED STATES PATENT OFFICE

2,441,454

NEWSPAPER STRIPING DEVICE

Auburn Taylor, Charleston, W. Va., assignor to
 The Goss Printing Press Company, Chicago, Ill.,
 a corporation of Illinois

Application April 11, 1944, Serial No. 530,463

5 Claims. (Cl. 91—12)

1

This invention relates to new and useful improvements in apparatus for applying a stripe or streak to a web of paper as it passes through a printing press, particularly for applying a stripe or streak of distinctive color for indicating a particular edition of a newspaper. A commonly used color is blue, and these editions are sometimes called "blue streak" editions.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side view showing a portion of a printing press on which is mounted a typical and illustrative embodiment of the present invention;

Fig. 2 is an end view of Fig. 1 looking from the right;

Fig. 3 is an enlarged vertical section taken on the line 3—3 of Fig. 2; and

Fig. 4 is a fragmentary sectional view of the detail taken on the line 4—4 of Fig. 3.

The striping device of the present invention is mounted on some suitable part of a printing press, preferably the former, so as to apply one or more stripes of colored ink to the printed newspaper in one or more outer margins thereof, or along a folded edge thereof. The most important object of the present invention is to provide a striping apparatus which is simple in structure and operation, which involves no moving or rotating parts, and which is variably positionable for accurately locating it with respect to the web.

The invention comprises one or more flat faced nozzles, supplied with ink, preferably by gravity, from an inkpot, which nozzles are positioned to press firmly against the moving web for applying a streak or stripe of ink to the web, of a width as determined by the width of the nozzle. An ink that is absorbed readily by the paper should be used, such, for example, as a water base ink or a thin oil ink. The nozzle should press fairly snugly against the web so that there is no lateral spreading or leakage of the ink, and this may be accomplished by providing a shallow recess in the former directly opposite the mouth of the nozzle so that the nozzle presses

2

the web a small amount into the shallow recess, the web being thereby tensioned over the mouth of the nozzle, and acting as a closure therefor.

The striping nozzles are mounted so as to be variably positionable laterally with respect to the printed web so that the colored stripe is accurately located in the desired margin. This is preferably accomplished by having the nozzles mounted on a guide, manually operated, threaded means being utilized for moving and setting the nozzles to the proper positions on their guides.

Ink is supplied to the several nozzles from inkpots, preferably individual inkpots so that different colored inks may be supplied, if desired, to different nozzles. In the preferred embodiment the nozzles and their respective inkpots are each movable as a unit for positioning them as above described.

The several nozzles and their respective inkpots are conveniently mounted on a bracket secured to the former of the press and this bracket, in addition to being readily attachable and detachable from the press, is variably positionable with respect to the former for giving adjustment of the nozzles with respect to the former.

It will be understood that the foregoing general description and the following detailed description as well, are exemplary and explanatory of the invention but are not restrictive thereof.

Referring now in detail to the drawings:

A bracket 2 is secured to a portion 4 of the framework of the press, and this bracket in turn supports a casting indicated generally at 6, in more or less parallel relationship with the usual former 8 of the press, over which former the web 10 passes after passing over guide rolls 12. The former 8 is provided with shallow recesses 14 located just below the margins of the printed web.

The stripe applying device of the present invention comprises a hollow, flat-faced, ink-applying nozzle 16, which as shown in Fig. 3 is adapted to press against the web 10 and to press the web slightly into the recess 14 for tensioning the web across the mouth of the nozzle, acting as a closure tight enough to prevent leakage. The width of the nozzle determines the width of the stripe. The nozzle is provided with a central passageway 18, opening into a valve seat 20 which cooperates with a closing valve 22. The nozzle is threaded into the tubular extension 24 of inkpot 26, said tubular member 24 being provided with a threaded bearing 27 for the threaded lower end of rod 28 carrying the valve 22. Ink from the inkpot 26 simply flows to the nozzles by gravity and the valve 22 is not intended as a needle valve control. Valve 22 is operated by turning wing nut 29. If the speed of

the web increases, more ink is drawn down into the nozzles.

In order to provide for the lateral positioning of the nozzles, casting 6 is provided with guide rods 30 and 32. Movable on these guide rods in suitable apertures is a support 34 for the inkpot and its nozzle, a lock collar 36 being keyed to the extension 24 of the inkpot, and this lock collar supports the inkpot and in turn rests on the guide 34.

In order to move the inkpot and its nozzle on the guide rods, one of the guide rods, such as 30, is provided with a screw thread cooperating with corresponding threads in the recess of the guide. Rod 30 is turnable by a manually operated knob (not shown), the operation of which moves the guides 34 back and forth on their guide rods, thereby moving the inkpots individually and their respective nozzles laterally with respect to the web.

Means are also provided for raising and lowering the nozzle 16 with reference to the paper 10. For this purpose the guide rod 32 is mounted eccentrically for rotation in its bushings and may be turned by the knob 38 attached to one end of the rod. Rod 32 fits in recess 32' so that rotation of the rod raises or lowers the nozzle 16 by pivoting around the guide rod 30. Rod 32 is preferably frictionally held so that accidental rotation does not occur.

The casting 6 carrying the nozzles and inkpots is slidably and variably positionable on the shelf 2' of the bracket 2 in any suitable way, such, for example, as by a bolt 40 engaging with 2' and engaging in a slot in the lower portion 42 of the casting 6. In order to move 6 and 42 back and forth on the shelf 2', there is provided a threaded adjusting screw 44 secured to a bearing 46 carried by bracket 2, the threaded rod engaging with extension 42. Turning of the threaded rod 44 by the knob 48 will move the casting 6 toward and away from the face of the former, thereby giving a close and accurate adjustment of the nozzles with respect to their distance from the former.

The adjustment, provided by the guide rod 32 and the adjustment provided by the variable positioning of the frame or casting 6 on bracket 22', each enables the nozzles to be positioned at different distances from the former for accommodating webs of varying thickness. In newspaper work, where this invention is used, there may be anywhere from one to eight thicknesses of paper passing over the former 8 and the described adjustments enable the nozzles to be set for any thickness. The adjustment provided by movement of 6 on the bracket 2 positions both ink nozzles, while the adjustments provided by rods 32 position the nozzles individually.

While the invention has been described as positioned over the former, it could be positioned over some other appropriate part of the press.

By suitable positioning of the two nozzles shown in Fig. 2, they may be arranged to make parallel stripes, as shown in Fig. 4. Such parallel stripes may be side by side, as shown in Fig. 4, or they could be spaced apart; the two stripes, for example, could be spaced apart by the width of one stripe and if red and blue inks were used for the stripes the effect would be that of a red, white and blue striping.

The invention in its broader aspects is not limited to the specific mechanisms shown and described but departures may be made therefrom

within the scope of the accompanying claims without departing from the principles of the invention and without sacrificing its chief advantages.

5 I claim as my invention:

1. A stripe applying device for a high speed printing press, comprising in combination a former, an ink-applying nozzle adapted to engage the web and to apply an ink stripe to the web as it moves over the former, and means for variably positioning said nozzle toward and away from the paper web, an ink pot above the nozzle and movable therewith as a unit, for supplying ink thereto, by gravity, and means for variably positioning said ink pot and nozzle as a unit laterally, with respect to the moving web.

10 2. A stripe applying device for a high speed printing press, comprising in combination, a former having a shallow recess therein, an ink applying striping nozzle position directly opposite said recess, so that a paper web passing over the former is pressed by said nozzle into said recess and is thereby tensioned over the mouth of the nozzle, an ink pot movable as a unit with said nozzle, and means for positioning said unit laterally with respect to the paper web.

15 3. A stripe applying device for a high speed printing press, comprising in combination with the former of a printing press, of a bracket carried by the frame of the printing press, ink-applying striping nozzles carried by said bracket, means for variably positioning said bracket with respect to the former, and means for laterally positioning said nozzles with respect to a printed web passing over the former so that the nozzles apply parallel stripes to said web.

20 4. A stripe applying device for a printing press, comprising a pair of nozzles, spaced apart laterally, said nozzles being adapted to press against a printed web and to apply parallel stripes thereto, means for variably positioning said nozzles individually with respect to said web, and means for moving both nozzles as a unit toward and away from the web, for accommodating webs of different thickness.

25 5. A stripe applying device for a printing press, comprising a pair of nozzles, each adapted to press against a printed web and to apply a stripe thereto, means for individually positioning said nozzles laterally with respect to said web, means for individually positioning said nozzles toward and away from the web, and means for moving both said nozzles as a unit, toward and away from the web.

30 55 AUBURN TAYLOR.
